UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-DELIVERY MECHANISM FOR PRINTING-MACHINES.

1,279,825.

Specification of Letters Patent. Patented Sept. 24, 1918.

Application filed December 28, 1914. Serial No. 879,325.

To all whom it may concern:

Be it known that I, HOWARD M. BARBER, a citizen of the United States, and resident of Stonington, in the county of New London 5 and State of Connecticut, have invented a new and useful Improvement in Sheet-Delivery Mechanism for Printing-Machines, of which the following is a specification.

The object of this invention is to provide 10 novel means for delivering whole width or slitted sheets flat either successively or in groups.

My invention includes means for cutting sheets from a traveling web, a rotary sheet 15 carrier which may be a slitting cylinder, an endless web feeding carrier which engages the web, carries it through the sheet cutting means and transfers the sheets cut therefrom to said rotary sheet carrier; a sheet delivery 20 device which may be an endless delivery carrier and a rotary transfer cylinder arranged to transfer the sheets from the rotary sheet carrier to the endless delivery carrier.

My invention more specifically includes 25 means whereby the cylinder which transfers the sheets from the rotary sheet carrier to the sheet delivery device may be used either as a means for transferring successive sheets from the rotary sheet carrier to the delivery 30 device or it may be used as a collecting cylinder for collecting thereon successive whole width or slitted sheets as the case may be, and transferring the collected group of sheets to the delivery device, a movable cam 35 being arranged to open the transfer cylinder grippers every second revolution of the transfer cylinder at the point of transfer to the grippers of the delivery device, friction pulleys being employed for holding the first 40 whole width or slitted sheets on the transfer cylinder in proper register while the grippers are open to receive the second whole width or slitted sheets.

A practical embodiment of my invention is 45 represented in the accompanying drawings, in which—

Figure 1 represents in side elevation so much of a sheet delivery mechanism for printing machines as includes my invention, 50 Fig. 2 is a detail section taken from front to rear just inside the near side frame,

Fig. 3 is a detail section showing the cams for operating the transfer cylinder grippers, and

55 Fig. 4 is a diagrammatic section taken

from front to rear centrally through the delivery mechanism.

The web is fed at a certain speed between the roll 1 and rollers 2. The means for cutting sheets from the traveling web is shown 60 as a pair of rotary cutters 3, 4, mounted on suitable shafts 5, 6, and having one set of coacting blades 7, 8.

The sheet receiving table is denoted by 9. A sheet delivery device is arranged to deposit the full width or slitted sheets either 65 successively or in groups upon the table 9, which delivery device is herein shown as an endless sheet delivery chain carrier 10 having head grippers 11 arranged at intervals 70 along the same.

A rotary sheet carrier, in the present instance a slitting cylinder 12, is mounted upon a shaft 13, which cylinder is shown as being provided with two sets of grippers 14, 15. 75

The means for transferring the sheets from the cylinder 12 to the sheet delivery device, is shown as a rotary cylinder 16 mounted on a shaft 17 and having a single set of grippers 18. Friction pulleys 19 bearing against the periphery of the transfer cylinder 16 are shown as mounted in yielding arms 20 carried by fixed arms 21 on the cross shaft 22.

A curved sheet guide 23 is also provided 85 partway around the periphery of the transfer cylinder 16.

An endless web feeding carrier, which is shown herein as an endless chain carrier 23, has, at intervals thereon, side grippers 24 90 carried to grasp the side edges of the web before the web reaches the rotary cutters 3, 4, carry the web through said rotary cutters and finally transfer the heads of the sheets cut from the web to the grippers 14 or 15 of 95 the cylinder 12. Guides 25, 26, serve to guide the web from the feed roll to the rotary cutters and a guide 27 serves to support the sheets from the rotary cutters to the cylinder 12. 100

A rotary sheet tucker 28 is mounted on a shaft 29 within the path of the endless carrier 23 in position to insure the grasping of the heads of the sheets cut from the web by the grippers on the cylinder 12 as the said 105 sheets are released from the grippers on the endless carrier.

One of the coacting rotary cutters is located within the path of the endless carrier 23 and the carrier is herein shown as down- 110

wardly inclined from the web roll 1 to a point beyond the cylinder 12.

The side grippers 24 are operated by fixed cams 30 at the proper point to grasp the side edges of the web near the beginning of the rectilinear portion of their travel away from the receiving end of the endless carrier.

Fixed cams 31 are arranged in position to open the side grippers 24 near the end of 10 the rectilinear portion of their travel toward the delivery end of the carrier at the proper time to transfer the sheets cut from the web to the grippers on the cylinder 12.

A fixed cam 32 is arranged in position to 15 successively operate the grippers 14, 15, of the cylinder 12 to cause them to close upon the heads of successive sheets as they are fed from the endless carrier 23 and a fixed cam 33 is arranged in position to open the grippers to transfer the heads of the sheets to 20 the grippers 18 of the transfer cylinder 16.

A fixed cam 34 is arranged in position to operate the grippers 18 of the transfer cylinder to cause them to receive successive 25 sheets from the grippers 14, 15, of the cylinder 12.

A cam 35 is carried by one arm of a rock lever 36 pivoted at 37, the other arm of which lever is provided with a stud or roller 30 38 traveling in the groove 39 of a rotary box cam 40 mounted on a shaft 41.

A gear 42 is carried by the box cam 40 and a gear 43 is mounted on the shaft 17 of the transfer cylinder. When the transfer 35 cylinder is utilized for transferring successive sheets from the cylinder 12 to the endless delivery carrier 10, the gears 42 and 43 are placed out of mesh, thus holding the cam 35 stationary. When the transfer cylinder 40 is used for collecting successive sheets, in the present instance two, from the cylinder 12 and transferring the group of sheets to the grippers 11 of the endless delivery carrier, the gears 42 and 43 are brought into 45 mesh so that the cam 35 is moved into position to open the transfer cylinder grippers 18 every second revolution thereof, at their point of transfer to the endless delivery carrier.

50 A fixed cam 44 is arranged in position to operate the successive head grippers 11 of the endless delivery carrier to cause them to receive the heads of the sheets from the transfer cylinder grippers 18.

55 A fixed cam 45 is arranged in position to operate the head grippers 11 to cause them to release the heads of the sheets at the proper time for delivery onto the sheet receiving table 9.

60 It is to be understood that where two sheets are collected on the transfer cylinder alternate head grippers on the endless delivery carrier may be removed.

Where the sheets are to be slit longitudinally of their travel into a plurality of

sheets, one or more slitting disks 46 may be provided in position to slit the sheets on the cylinder 12.

The geared connection between the several parts is as follows: The shaft 13 of the cylinder 12 is driven through the train of gears 47, 48, 49, 50. The rotary cutters are driven from the gear 48 through the gear 51 and the endless web feeding carrier 23 has its side chains exteriorly toothed and driven by 75 gears 52 on the shaft 5 of the rotary cutter 3 at the speed of the traveling web. The transfer cylinder shaft 17 is driven from the cylinder shaft 13 through the gears 53, 54. The endless delivery carrier 10 is driven 80 from the gear 54 through the gears 55, 56, 57. The shaft 58 of the slitter 46 is driven from the shaft 13 through the gears 53, 59. The shaft 29 of the rotary tucker is driven from the shaft 13 through the gears 53, 60. 85 The geared connection between the several parts is such that the cylinder 12 has a surface speed slightly higher than the speed of the traveling web and of the surface speed of the web feeding endless carrier. The 90 transfer cylinder and the endless delivery carrier have the same surface speed as the cylinder 12. This cylinder 12 has each of its sheet carrying surfaces a little longer than the sheet thereby leaving an open space 95 between the sheets sufficient to permit the coaction of the transfer cylinder grippers with the grippers on the cylinder 12 when taking the sheets from said cylinder.

In operation: The side grippers of the endless web feed engage the side edges of the traveling web at the speed thereof and carry the web through the rotary cutters where the sheet is cut from the web. These side grippers feed the head of the sheet to the 105 grippers on the cylinder 12, the rotary tucker 28 insuring the accurate grasping of the head of the sheet by said grippers on the cylinder 12 absolutely square with the side edges of the sheet. If desired, the sheet is 110 slit longitudinally of its travel on the cylinder 12 and the slit sections are then transferred to the transfer cylinder grippers 18.

If the sheet is not to be slit, the whole width sheet is transferred to the said grippers 18. The whole width or slitted sheets are transferred successively to the head grippers 11 of the endless delivery carrier 10 or, if so desired, the whole width or slitted sheets may be collected by the grippers 120 18 into groups and the groups transferred to the head grippers 11. In the former instance, the cam 35 is held stationary by putting the gears 42, 43, out of mesh and in the latter instance this cam is rendered movable 125 by putting the said gears into mesh.

The head grippers 11 deliver the whole width or slitted sheets onto the sheet receiving table 9.

While I have shown the sheets as slit into 130

pairs, it is obvious that the sheets may be fed through the mechanism without slitting and also that the sheets may be slit longitudinally into any number of smaller sheets, 5 as desired.

It is also to be seen that the sheets either whole width or slitted, may be delivered successively or in groups, as desired.

By the term "cylinders" wherever used, I 10 wish to include any means suitable for carrying the sheets through the prescribed paths and by the term "grippers" I wish to include any means suitable for engaging the sheets to lead them through their path of 15 travel.

By maintaining control of the sheet after it is cut from the web until it is positively engaged by the grippers on the cylinder 12, I am enabled to feed the sheet with its head 20 absolutely square with respect to its side edges so as to insure the accurate slitting of the sheet parallel with said side edges when it is desired to slit the sheets.

Furthermore, by the use of the endless 25 web feeding carrier, for feeding the web through the cutters and then transferring the sheet cut therefrom to the slitting cylinder, the mechanism for handling the web and sheets is materially simplified.

30 It is evident that changes might be resorted to in the form, construction and arrangement of the several parts without departing from the spirit and scope of my invention; hence I do not wish to limit myself strictly to the structure herein set forth, 35 but

What I claim is:—

1. In a machine of the character described, means for cutting sheets from a 40 traveling web, an endless delivery carrier, a rotary sheet carrier, means arranged to engage the web, carry it through the cutting means and transfer the sheets cut therefrom to the rotary sheet carrier, and a transfer 45 cylinder arranged to transfer the sheets from the rotary sheet carrier to the endless delivery carrier.

2. In a machine of the character described, means for cutting sheets from a 50 traveling web, a sheet delivery device, a rotary sheet carrier, means arranged to engage the web, carry it through the cutting means and transfer the sheets cut therefrom to the rotary sheet carrier, and means arranged 55 to take sheets successively from the rotary sheet carrier, collect them in groups, and transfer said groups to the delivery device.

3. In a machine of the character described, means for cutting sheets from a 60 traveling web, an endless delivery carrier, a rotary sheet carrier, means arranged to engage the web, carry it through the cutting means and transfer the sheets cut therefrom to the rotary sheet carrier, and a transfer 65 cylinder arranged to take sheets successively

from the rotary sheet carrier, collect them in groups and transfer said groups to the endless delivery carrier.

4. In a machine of the character described, means for cutting sheets from a 70 traveling web, a sheet delivery device, a rotary sheet carrier, means arranged to engage the web, carry it through the cutting means and transfer the sheets cut therefrom to the rotary sheet carrier, sheet slitting 75 means, and means arranged to take slitted sheets successively from the rotary sheet carrier, collect them in groups and transfer said groups to the delivery device.

5. In a machine of the character described, means for cutting sheets from a 80 traveling web, an endless delivery carrier, a rotary sheet carrier, means arranged to engage the web, carry it through the cutting means and transfer the sheets cut therefrom to the rotary sheet carrier, sheet slitting means, and a transfer cylinder arranged to take slitted sheets successively from the rotary sheet carrier, collect them in groups and transfer said groups to the endless delivery 85 carrier.

6. In a machine of the character described, means for cutting sheets from a 90 traveling web, a sheet delivery device, a rotary sheet carrier, means arranged to engage the web, carry it through the cutting means and transfer the sheets cut therefrom to the rotary sheet carrier, and means arranged either to transfer the sheets successively from the rotary sheet carrier to the 95 delivery device or to take such sheets successively from the rotary sheet carrier, collect them in groups and transfer said groups to the delivery device.

7. In a machine of the character described, means for cutting sheets from a 100 traveling web, an endless delivery carrier, a rotary sheet carrier, means arranged to engage the web, carry it through the cutting means and transfer the sheets cut therefrom to the rotary sheet carrier, and a transfer 105 cylinder arranged either to transfer the sheets successively from the rotary sheet carrier to the endless delivery carrier or to take such sheets successively from the rotary carrier, collect them in groups and transfer said groups to the endless delivery carrier.

8. In a machine of the character described, means for cutting sheets from a traveling web, a rotary sheet carrier, a sheet delivery 110 device, means arranged to engage the web, carry it through the sheet cutting means and transfer the sheets cut therefrom to the rotary sheet carrier and means arranged to take the sheets successively from the rotary 115 sheet carrier, collect the same in groups and transfer said groups to the delivery device.

9. In a machine of the character described, means for cutting sheets from a traveling web, a rotary sheet carrier, an endless de- 120

125

130

livery carrier, means arranged to engage the web, carry it through the sheet cutting means and transfer the sheets cut therefrom to the rotary sheet carrier and a transfer cylinder arranged to take the sheets successively from the rotary sheet carrier, collect the same in groups and transfer said groups to the endless delivery carrier.

10. In a machine of the character described, means for cutting sheets from a traveling web, means for slitting the sheets longitudinally of their travel, a sheet delivery device, means arranged to engage the web, carry it through the sheet cutting means and transfer the sheets cut therefrom to the slitting means, and means arranged to take the sheets successively from the sheet slitting means, collect the slit sheets in groups and transfer said slitted groups to the delivery device.

11. In a machine of the character described, means for cutting sheets from a traveling web, means for slitting the sheets longitudinally of their travel, an endless delivery carrier, means arranged to engage the web, carry it through the sheet cutting means and transfer the sheets cut therefrom to the sheet slitting means, and a transfer cylinder arranged to take the sheets successively from the sheet slitting means, collect the slitted sheets in groups and transfer said slitted groups to the endless delivery carrier.

12. In a machine of the character described, means for cutting sheets from a traveling web, a rotary cylinder, means for

slitting the sheets longitudinally of their travel thereon, an endless delivery carrier, means arranged to engage the web, carry it through the sheet cutting means and transfer the sheets cut therefrom through the slitting cylinder, and a transfer cylinder arranged to take the sheets successively from the slitting cylinder, collect the same in groups and transfer said groups to the endless delivery carrier.

13. In a machine of the character described, means for cutting sheets from a traveling web, a rotary cylinder, means for slitting the sheets longitudinally of their travel thereon, an endless delivery carrier, means arranged to engage the web, carry it through the sheet cutting means and transfer the sheets cut therefrom through the slitting cylinder, and a transfer cylinder arranged to take the sheets successively from the slitting cylinder, collect the same in groups and transfer said groups to the endless delivery carrier, the said sheet cutting and feeding means traveling at the surface speed of the web and the said slitting cylinder, transfer cylinder and endless delivery carrier traveling at a higher speed.

In testimony, that I claim the foregoing as my invention, I have signed my name in presence of two witnesses, this twenty first day of December, A. D. 1914.

HOWARD M. BARBER.
